(57) **CLAIM**

The ornamental design for a locking shower caddy, as shown and described.

DESCRIPTION

FIG. 1 is a front perspective view of a locking shower caddy article embodying my design.

FIG. 2 is a reduced front perspective view of a locking shower caddy article embodying my design, illustrating an open front door panel to show the inside of the caddy, without an inner shelf.

FIG. 3 is a reduced front perspective view of a locking shower caddy article embodying my design, illustrating an open front door panel to show the inside of the caddy, including an inner shelf.

FIG. 4 is a reduced front plan view of a locking shower caddy article embodying my design.

FIG. 5 is a reduced front plan view of a locking shower caddy article embodying my design, illustrating an open front door panel to show the inside of the caddy, without an inner shelf.

FIG. 6 is a reduced front plan view of a locking shower caddy article embodying my design, illustrating an open front door panel to show the inside of the caddy, including an inner shelf.

FIG. 7 is a reduced top view of a locking shower caddy article embodying my design.

FIG. 8 is a reduced bottom view of a locking shower caddy article embodying my design.

FIG. 9 is a reduced right, side view of a locking shower caddy article embodying my design.

FIG. 10 is a reduced left, side view of a locking shower caddy article embodying my design.

FIG. 11 is a reduced back, side view of a locking shower caddy article embodying my design; and,

FIG. 12 is a back perspective view of a locking shower caddy article embodying my design.

The broken lines showing in the figures is included for purposes of illustrating portions of the locking shower caddy and form no part of the claimed design.

The mark, "SHLOCKER" shown in broken lines, and forming no part of the claimed design is a registered trademark owned by the applicant, Tula Industries, LLC.

1 Claim, 10 Drawing Sheets
